UNITED STATES PATENT OFFICE.

LEO KUCAK, OF CLEVELAND, OHIO, ASSIGNOR OF ONE-HALF TO VIRGINIA LEA KUCAK, OF CLEVELAND, OHIO.

DOOR-RETAINING DEVICE.

Application filed August 3, 1927. Serial No. 210,248.

This invention relates to a device for retaining garage doors, or doors of similar buildings, in open position. The general object of the invention is to provide a door retainer which may be easily constructed from a minimum number of simple parts, and which will hold the door firmly in the desired position.

A further object is to provide a door retaining device which shall be so arranged that the likelihood of sticking or jamming of the parts, by reason of the accumulation of foreign material, is reduced to a minimum.

Another object is to provide a retaining device which may be easily adapted to various styles of garage construction, and which shall be easily adjustable for different overhead clearance distances between the door and garage hood or the like, as well as adjustable for different door thicknesses.

A further object is to provide a door retainer which may be made to engage the door at the most effective angle, irrespective of the angle of the door with reference to the building. Further objects and features of the invention will become apparent from the following description relating to the accompanying drawing, wherein I have shown my preferred forms. The essential characteristics are summarized in the claims.

In the drawing, Fig. 1 is a fragmentary side elevation of one common type of garage, partly broken away to show the position of the door retaining device; Fig. 1^a is a central vertical cross sectional view of the preferred form of retaining device taken at right angles to the showing of Fig. 1; Fig. 1^b is a plan view of the device shown in Fig. 1^a and showing in broken lines the manner of application to hold the door at an acute angle to the building; Fig. 2 is a similar fragmentary side elevation of a different type of garage showing a modified form of retaining device; Fig. 3 is a side elevation of a still different form of retaining device adapted for application to a building such as shown in Fig. 2; and Fig. 3^a is a plan view of the form of device shown in Fig. 3.

Referring in detail to the drawing and indicating the various parts by suitable characters, A is the side wall of a garage and B the front wall thereof. C is the roof portion of the garage hood and D the ceiling portion, the latter portion being shown as joining the

forward edge of the roof and the front wall of the garage. The door is mounted flush with the front wall and the upper edge of the door usually clears the ceiling D by the distance of from three to six inches when swung outwardly on the hinges. The arrangement of parts, shown in Fig. 1^a, is especially adapted to this type of construction.

As shown in Fig. 1^a, the device comprises a vertical member 1 preferably formed of iron pipe, thereby combining lightness and strength, a bracket 2 for supporting the pipe, a latch 3 for engaging the door and a latch releasing member shown as a chain 4. A set screw 7 is preferably employed to hold the pipe in rigid position with the latch just low enough to be engaged and lifted by the upper edge of the door. The bracket 2 has an attaching flange 5 adapted to receive fastening members, such as bolts or screws, screws being indicated at 6. The screws directly engage the ceiling member of the hood. The latch 3 as shown is supported and guided by slots 9 and 10 and is pivoted intermediately of its ends on a pin 12 passing through from one side of the pipe to the other. The pin is preferably riveted over at its ends to hold it in place. The end of the latch at the left of the pivot (as shown in Fig. 1^a) is adapted to extend toward the door and is heavy enough to normally rest at the bottom of the slot 9. This end of the latch is enlarged at 13 and has a rounded or camming surface 14 adapted to engage the edge of the door as the door swings toward the member 1, whereby the latch is lifted. As the door E comes into contact with the member 1, the enlarged end of the latch drops by gravity and a shoulder 15 adjacent the cam surface holds the door in place.

If desired, and to accommodate different thicknesses of doors I may provide additional openings, such as 16, only one being shown, for embracing the pivot pin 12. Thus, if the door is thicker, in proportion to the parts than as shown, the pin would engage the additional opening 16 thus increasing the distance between the shoulder 15 and the member 1.

The releasing member 4 may be of any convenient length and, as shown, depends from a ring 28 in an opening 29 near the rear end of the latch. When it is desired to close

the door the operator simply reaches past the edge of the door, pulls downwardly on the chain and swings the door to closed position.

5 As shown in Fig. 12 the pipe is externally threaded for a considerable distance at 18 to engage complementary threads in the bracket and the set screw 7 engages the threads to lock the pipe in vertically adjusted position. The adjustment is only necessary during installation and is provided for on account of variation, in different buildings, of door and hood clearance. The ceiling member may have a hole 15 bored therein in registration with the pipe and large enough to permit the pipe to pass through into the idle space above the ceiling member in case the door swings closer to the hood than as shown in full lines. Such adjustment simply raises the latch, for example, as shown in broken lines in Fig. 1^a, to cooperate with a correspondingly raised door, also shown in broken lines. The construction may be simplified by omitting the 25 threaded connection between the pipe and bracket and employing a sliding fit between these members. This is not illustrated. In Fig. 1^b the showing in full lines illustrates the position of the parts with the door extending from the building at right angles. The showing in broken lines in this figure brings out the desirability of so mounting the abutment member 1 and the latch that these parts may be swung to any angle with 35 reference to the bracket. For example, where conditions are such that the door E may be opened to a position such as shown in broken lines, the bracket may still be placed true with the building lines in approximate position, the pipe then turned to cause the latch to extend at right angles to the door, as shown, and finally locked securely in place by the set screw.

In Fig. 2 the garage has side and front 45 walls A and B as before, but in this case there is no hood arrangement. In order to support the vertical member 1 far enough away from the front wall to securely hold the door without putting excessive strain on the hinges, I provide an overhanging bracket 50 having a portion 21 adapted to be threaded to, or to slidably engage the member 1 as before, and which extends horizontally at 22 and vertically as at 23 to provide for attachment to a vertical wall. Suitable bolts or screws may pass through the vertical portion 23 and the front wall to hold the bracket in place. The latch member 3 may be extended at right angles to the door when the 55 latter is in open position as before by turning the pipe and then locking it in place. If desired, this form of bracket may be lightened by providing openings in the webs leaving, of course, simply enough material to 60 take the strains when the door is shaken as

by wind, and one or more of the webs may extend upwardly from the portion 21, as well as laterally, to take such strain.

In the case of buildings of the type shown in Fig. 2 it is often desirable to support the latch at a considerable distance from the front wall in order to engage the door at a point remote from the hinge axis. This is particularly true when the door is limited to an open position nearly normal to the wall as in the case of double garages, where it is undesirable that the door be swung completely open, but rather just enough to allow the entrance and exit of the car. For such buildings I propose to use a pipe, such as shown at 30 in Fig. 3, having a horizontal portion 31 supported at one end as by a bracket member 32 similar to that shown in Fig. 1^a, this bracket being secured to the front wall in any suitable manner. Near its outer end the pipe 30 bends downwardly and extends vertically as at 33, and the vertical portion is slotted to receive the latch 3 as before. Obviously, unless the member 30 is very rigid and is very rigidly attached to the building, the whole device could be easily damaged by slamming the door against the pipe. To brace the pipe I propose to provide a strut member 35 secured to the pipe close to the latch and extending upwardly and laterally from the pipe to a convenient attachment such as an eye-bolt 37 secured to the building wall. The end of the strut, assuming that the strut is made from bar stock, may be curled over as at 38, to embrace the eye-bolt. The end of the member 35 may pass through the vertical portion of the pipe and be riveted over as at 39 beyond the pipe.

From the above description it will be seen that I have provided a sturdy retaining device suitable for use for garage doors or the like, wherein the parts are few in number, very simple and easily made from inexpensive materials following common shop practices. Further, by my arrangement a single device may be used with garage constructions of varying designs by very simple adjustments.

I claim:

1. A door retaining device comprising in combination, a downwardly extending member arranged to extend in the path of the door at the upper edge thereof, a latch bar extending transversely of and pivotally supported by said member and having a cam end adapted to be engaged by the door, said bar having a shoulder for holding the door in position against said member, and means for releasing the latch bar.

2. A door retaining device comprising in combination, a support adapted to be secured to a building, a member depending substantially vertically from the support, a recess near the lower end of the said mem-

ber, a latch bar pivotally supported in the recess and having a cam end adapted to be engaged by the door, a shoulder on the bar for holding the door in position against said 5 depending member, and means for releasing the latch.

3. In a retaining device for doors, a bracket adapted to be secured to a building above the path of a door, said bracket having an 10 opening, a vertically extending member adjustably engaging said opening, a latch bar pivotally supported by said vertically extending member and having a cam end and a shoulder to engage and retain the door in 15 place against said member, means carried by the bracket for fastening the vertical member in adjusted positions, and means depending from the end of the latch opposite the end to be engaged by the door for releasing the latch to permit the door to be 20 closed.

4. In a garage door retaining device, a vertically adjustable member adapted to extend downwardly with its lower end in the 25 path of a door, a recess near the lower end of said member, a latch bar passing through the recess and having a cam and shoulder at one end for engaging the door, a pin pivotally supporting the latch, and means attached to the end of the latch opposite said 30

cam and shoulder and arranged to depend alongside the retained door for releasing the latch.

5. In a door retaining device, a bracket adapted to be secured to a garage building 35 above the path of movement of a door thereof, a circular pipe depending from the bracket and adjustably secured thereto, longitudinally offset slots in opposite sides of the pipe near the bottom thereof, and a 40 latch bar pivotally supported in said slots and normally resting at one end in one of the slots in position to be lifted by the door, and means for releasing the latch bar.

6. A door retaining device comprising in combination, a support adapted to be secured to a building, a member turnably mounted in and vertically adjustable relative to the support, a latch bar pivotally supported by the said member and having a cam end 45 adapted to be engaged by a door of the building, a shoulder on the bar for holding the door in position against said member, means for releasing the latch, and means carried by the support for fastening the member in 50 fixed position with the latch extending normal to the door.

In testimony whereof, I hereunto affix my signature.

LEO KUCAK.
